Primary Examiner — Sandra L Morris(74) *Attorney, Agent, or Firm* — Sorell, Lenna & Schmidt, LLP(57) **CLAIM**

The ornamental design for a wide mouth food container, as shown and described.

DESCRIPTIONFIG. 1 is an isometric view of a wide mouth food container;
FIG. 2 is a side view of the container;
FIG. 3 is a front view of the container;
FIG. 4 is a side view of the container;
FIG. 5 is a rear view of the container;
FIG. 6 is a top view of the container; and,
FIG. 7 is a bottom view of the container.

The broken lines are for the purpose of illustrating structure and form no part of the claimed design.

1 Claim, 7 Drawing Sheets---
